UNITED STATES PATENT OFFICE.

EMMIT G. GRIFFITH, OF BROOKLYN, NEW YORK, ASSIGNOR, BY MESNE ASSIGNMENTS,
TO UNDERWOOD COMPUTING MACHINE COMPANY, A CORPORATION OF NEW YORK.

COMBINED TYPE-WRITING AND COMPUTING MACHINE.

1,263,881.

Specification of Letters Patent. Patented Apr. 23, 1918.

Application filed September 23, 1913. Serial No. 791,264.

To all whom it may concern:

Be it known that I, EMMIT G. GRIFFITH, a citizen of the United States, residing in Brooklyn borough, city of New York, in the 5 county of Kings and State of New York, have invented certain new and useful Improvements in Combined Type-Writing and Computing Machines, of which the following is a specification.

10 This invention relates to an improvement in combined typewriting and computing machines of the Underwood-Hanson type and is an improvement on applications of Frederick A. Hart, Nos. 466,836 and 466,837, filed 15 December 10, 1908 (or the latter's substitute and continuation, No. 838,930, filed May 16, 1915).

One of the objects of this invention is to economize space, or to provide a greater 20 number of computing heads or totalizers for a given space. For example, in the form of the invention illustrated, the advantage of four computing heads or totalizers is afforded, where only three might otherwise 25 be used.

Heretofore it has usually been necessary on a typewriter to devote a separate computing head to each column, whether the column is wide or narrow; and where there 30 is only room for three computing heads in the machine, it makes it impossible to print more than three narrow columns on a sheet, whereas it is sometimes desired to print four or five narrow columns, and at other times 35 to print only three wide columns, on the same machine.

This invention increases the capacity of the machine, by making it possible to use two totalizers, either for two wide columns, 40 or for four narrow columns, or for one wide column and two narrow columns, as may be desired; at the same time the amounts written in all columns may be accumulated upon the grand total computing head.

45 This may be stated in another way by saying that there is a need of sometimes using small and sometimes large numbers in different columns, to fill which need small computing heads or totalizers are provided 50 where small numbers are to be computed, and large computing heads provided where large numbers are to be computed; and there is also provided a gross computing head to act simultaneously with the others 55 and therefore compute both large and small

numbers, so as to obtain a gross total. There may be provided one or more computing heads of a capacity of 9,999,999.99. There may also be provided two or more other computing heads limited to smaller numbers, such as 999.99 and 99.99. Further, there may be provided a gross computing head capable of computing 9,999,999.99, to run up the gross total of all the numbers added in the first three or more computing 65 heads.

This is, then, the problem that presents itself, how to preserve all of the old advantages, to use the adding head for writing and adding wide columns when desired, and 70 at the same time adapt it so that two narrow columns could be written and added on the work-sheet in the place usually occupied by each wide column.

In this type of machine, the numeral keys 75 cause the types to print and also set up the number by means of index-pins. Subsequently a general operator advances the bars which bear the set pins, and turn the number wheels accordingly. The computing 80 wheels are quite large and wide spread so as to be plainly visible. They therefore occupy a space considerably greater than the same number of accordant letter spaces as typewritten to form a record of the digits 85 of the numbers computed. In order to have a compact machine then, the number of computing wheels in all is limited, or, in other words, the number of major totalizers is limited. But by splitting or dividing the 90 major totalizer into smaller or minor totalizers to correspond with the narrow columns of small numbers computed, a greater capacity for a given space than has heretofore been available is made use of. 95

The index-pins are mounted on denominational bars which are raised *seriatim*, so that when a numeral key is struck, the corresponding index-pin will be set on the particular bar which at the time is raised above 100 its fellows. The bars are raised by means of a tappet carried by the typewriter carriage. The carriage travels from right to left, and the computing passes from left to right in the computing heads; the necessary inversion for raising the proper bars being accomplished through transposition linkages, which are operated by the tappets on the carriage. 105

Heretofore when using a tappet or dog on 110

the typewriter carriage for displacing the bars which carry the indexing-pins (to enable the pins to be depressed by the numeral keys of the typewriter), it has been necessary for the tappet or dog to operate every one of the jacks in the computing head, and thereby displace every one of the index-pin bars. This would occur during the progress of the carriage, even if only a narrow column were being written on a page. It is necessary that the carriage shall have traveled a certain distance carrying one tappet clear of a set of jacks before another tappet can engage its corresponding set of jacks to index digits for the following column. By this improvement, the necessary lateral movement of the tappets and thus the necessary travel of the carriage required for indexing in a plurality of columns, are reduced. This improvement also has special application even where no tandem or simultaneous computation is done, as in simple cross addition.

In limiting the lateral movement of the tappets and in concentrating the computing range, the effective paths of travel of the tappets must necessarily overlap each other, so that the several tappets may not only pass through the range of their own associated jacks which they are designed to operate, but also pass by the jacks corresponding to other tappets and which it is not desired to have them operate.

In order to avoid the contingency of the several tappets operating jacks belonging to other computing heads than those for which the particular tappets are set, the tappets are made of different effective lengths and are provided with pawls or dogs located at different points along their lengths with respect to the pawls or dogs on the other tappets. These dogs or pawls are then so located that they will come into engagement solely with jacks which they are designed to operate. To do this, the jacks themselves must be of different effective lengths. That is to say, each computing head or section of a computing head, where a computing head is divided into a plurality of minor totalizers, is provided with a set of jacks of a length and form designed to be actuated solely by the accordant tappet or tappets. In other words, suppose that there are computing heads A, B and C, B the head being divided into a plurality of minor computing heads or totalizers to be designated as B¹ and B², then the computing head A will have a series of jacks of a certain form and length, which will be actuatable solely by a tappet of a corresponding effective length. The sections or minor totalizers B¹ and B² being arranged right alongside each other, may be operated successively by a single tappet, the two sets of jacks and the tappet being of corresponding lengths. The lengths of these

jacks, however, may be such that the tappet which operates them, will, when it comes into the range of the first set of jacks corresponding to the computing head A, slip idly past the same without the dog or pawl thereon coming into engagement with these jacks.

For the last computing head, that is, the head C, the jacks may be arranged so that they may be operated concomitantly with those of the computing head A, and also concomitantly with those of the two minor computing heads B¹ and B², whereby the computing head C may be used as a gross totalizer. That is to say, the jacks of this last computing head may be designed to permit the indexing of large numbers at the same time that such numbers are computed in the large computing head A, and also index two sets of small numbers at the same time that such numbers are computed in the two minor totalizers or computing heads B¹ and B². To do this, the jacks of this computing head C are arranged in two sections. All of the jacks have an effective length such that a single tappet of right length with the dog or pawl thereon properly positioned, may actuate all of them to correspond with the actuation of all of the jacks of the computing head A. One section of these jacks, that is, the section corresponding to the four digits of lowest denomination, may be extended beyond the remainder of the jacks for this computing head, so as to be operated, in addition to the one of the tappets just mentioned, by a second type of tappet which has its dog positioned thereon so as to clear the jacks corresponding to the four digits of highest denomination, but located so as to operate the extended jacks corresponding to the four digits of lowest denomination. This latter type of tappet will actuate these jacks of lower denomination at the same time that the jacks of the minor totalizers B¹ and B² are actuated, so as to enable the computing head C to compute concomitantly with the minor computing heads B¹ and B².

Inasmuch as the computing heads B¹ and B² operate successively, there will be provided two tappets capable of actuating the four digit jacks of lower denomination, and these tappets will come into play successively corresponding to the activity of the two minor computing heads B¹ and B². The tappet which operates the two sets of jacks corresponding to the minor computing heads B¹ and B², has its dog so located thereon that it will escape past all of the jacks of the totalizer C. On the other hand, the tappet which actuates all of the jacks of the totalizer C, has its dog located at such a point that it will escape all of the jacks of both the minor totalizers B¹ and B².

It will be understood that while in this example only one large totalizer and two

small totalizers are used in connection with a gross totalizer, the number of totalizers may be varied to suit the character of work to be done, either by adding others or by dropping some of those described.

5 Other features and advantages will hereinafter appear.

In the accompanying drawings—

10 Figure 1 is a plan view with parts broken away to show the underlying structure and showing the typewriter carriage as having traveled from its initial position at the right.

15 Fig. 2 is a vertical section taken from front to rear, with many parts omitted for the sake of simplicity.

20 Fig. 3 is a diagrammatic view illustrating the action of the tappets and their dogs in camming the jacks of the different computing heads and showing the same in the initial position with the first jack of the major computing head and the accumulating computing head or cross totalizer in the act of being lifted.

25 Fig. 4 is a view similar to Fig. 3, with the exception that the carriage has traveled farther along and the first jack of the first minor computing head is being actuated at the same time that the jack corresponding to 30 tens is being actuated in the gross or cross totalizer.

35 Fig. 5 is a diagrammatic view similar to Figs. 3 and 4, with the exception that the carriage has traveled still farther along and is in the act of bringing a pair of tappets into coöperation one with the first jack of the second minor totalizer, and the other with the jack corresponding to tens in the gross or cross totalizer.

40 Fig. 6 is a diagrammatic spread perspective view showing the relation of three different types of jacks to the three different types of tappets, and showing how two of the jacks are operable solely by one type of 45 tappet different for each and how the third jack corresponding to the set which controls the columns corresponding to 99.99 of the gross or cross totalizer is actuatable by two different types of tappets.

50 Fig. 7 is a fragmentary perspective view of a portion of the transposition linkages whereby the order of succession is inverted to make the denominational columns of the carriage which travels from right to left, correspond with the denominational columns of the computing mechanism in which the computing travels from left to right.

55 Figs. 8, 9 and 10 are perspective views corresponding respectively with Figs. 3, 4 and 5.

60 Fig. 11 is a plan view showing a modified form of the invention, in which the sets of jacks for the minor totalizers are made of different lengths, so that they can be actuated by different tappets placed at any point

along the carriage, giving a wide range at which columns of small numbers can be located while the minor totalizers which compute them are located right alongside of one another.

70

Numerical keys 1 and alphabet keys 2 depress key levers 3 to rock bell cranks 4 to swing type-bars 5 up rearwardly against the front side of a platen 6 mounted on spring-driven carriage 7. The latter travels step by step, controlled by an escapement mechanism 8. A rack 9 on carriage 7 engages a pinion 10 connected to an escapement wheel 11, which is controlled by dogs 12, rocked by a universal frame 13, which receives its motion from heels 14 carried by type-bars 5.

75

The numeral keys 1 not only write the numbers on the work-sheet carried by the platen 6, but also depress links 15 to engage arms 16 and rock shafts 17 carrying these arms. These rock shafts 17 each actuate a transverse linkage 18 to depress or set index-pins 19. These index-pins are mounted on denominational bars 20, each bar carrying nine, to correspond with the numeral keys. The pins extend in transverse rows corresponding to the linkages 18, so that when any one of the bars 20 is in elevated position at the time that a numeral key 1 is struck, the corresponding linkage depresses the subjacent pin 19 on the raised bar, which afterward falls. The set pins compose a number, to predetermine the extent of longitudinal movement of the bars 20. It will be noted in passing that the number wheels of the computing head are wide-spread and large, and occupy in the aggregate a denominational area considerably greater in extent than the jacks 34. This means that the number wheels extend over a linear distance considerably greater than the corresponding number of letter spaces of according denominations as written on the work-sheet. This gives room for the actuating mechanism for the number wheels, and also permits the latter to be readily visible and to have comparatively large numbers inscribed on their peripheries. For this purpose the depressed

80

100 pins are engaged by a cross bar 21 on a general operator 22, so that racks 23 on the front ends of the bars may rotate pinions 24 carried by dial or number wheels 25. The general operator 22 may be actuated in any suitable manner, as by being provided with one or more racks 26 engaged by gears 27, which in turn are rotated by segments 28 on a rock shaft 29, oscillated by a crank 30.

105

110 To raise the pin-bearing denominational bars 20 section, the carriage 7 carries, on a rack or bar 31, tappets 32, adjustable therewith to vary the position of the computing zone or column which they control. Each tappet 32 includes a dog 33 to rock or turn jacks 34, pivoted intermediate their ends on 115

120

125

130

135

140

145

150

a rod 35 and at their rear ends arranged to depress thrust links 36.

Each of the thrust links 36 is arranged to rock a bell crank 37, which in turn engages a downwardly-extending finger 38 on a link 39. Each of the links 39 has a parallel in a link 40, which is connected thereto at both ends by means of pivotally-mounted bell cranks 41 and 42. The links 39 are provided with upstanding fingers 43 beneath the index-pin bars 20, to raise the same one at a time. The bell cranks 37 are graded in length to engage the fingers 38, which are arranged in echelon on the links 39 and extend forwardly from right to left. The fingers 43 are also arranged in echelon but extend forwardly from left to right. This transposition linkage mechanism inverts the order of action of the jacks 34 upon the bars 20, which are operated in order from highest to lowest denominations.

At Fig. 1 there are seen three computing heads or totalizers A, B and C with their dial wheels 25. There is a set of the index-pin bars 20 for each of the computing heads A, B and C, and the key-operated linkages 18 extend across all of these three sets of pin bars, so as to be capable of setting pins on any of them, or on two or more bars simultaneously, in the several sets.

The middle computing head or totalizer B is a twin totalizer, being composed of two minor computing heads operable independently of each other. One of these two minor computing heads or totalizers has a capacity of 999.99, and the other of 99.99.

We have, in effect, four totalizers: A, which will be called the major totalizer and which has a capacity of nine digits; B¹, which will be called the first minor totalizer and which has a capacity of five digits; B², which will be called the second minor totalizer and which has a capacity of four digits; and C, which will be called the gross totalizer and which has a capacity of nine digits. The gross totalizer C performs cross-computation, and is arranged to accumulate not only those numbers that are carried into the major totalizer A, but also individually the numbers that are carried into both the two minor totalizers B¹ and B².

The jacks 34 in each set are of equal length, but of different length from those in the other sets, and the dogs 33 on the tappets 32 are accordingly placed some forwardly and some backwardly, or in different transverse vertical planes, so that each dog may actuate solely the jacks which it is intended to actuate.

60 The tappets 32 are then of several kinds. 32A designates the tappet which controls the jacks of totalizer A.

32AC is the tappet which controls all of the jacks of the gross totalizer C, whenever 65 tappet 32A is engaged with jacks 34A.

32B is the tappet which controls successively the sets of jacks for both the minor totalizers B¹ and B².

32B¹C is the tappet which controls the set of jacks corresponding to the digits of 70 lowest denominations associated with the gross totalizer C, whenever tappet 32B is engaged with jacks 34B¹.

32B²C is the tappet which controls the same lowest denomination jacks of gross 75 totalizer C, whenever tappet 32B is engaged with jacks 34B².

The jacks 34 then are of different lengths, to correspond to the positioning of the dogs 33 which actuate them and are indicated 80 with numbers corresponding thereto, to wit: 34A, 34B¹, 34B², 34AC (which last applies to all of the jacks of the gross totalizer C), and 34AB¹B², which applies to the jacks corresponding to the four lowest digits of 85 the gross totalizer C.

It will be seen by reference to Figs. 1, 3 and 6, that one group of the jacks 34AC corresponding to the four highest digits, are the shortest and can only be actuated by that 90 tappet 32AC which has the rearmost dog 33, because their teeth 50 are set too far back to be engaged by any other tappet.

The next longest jacks are those designated as 34AB¹B², which form a portion of 95 the same major group 34AC and correspond with the four lowest digits of the totalizer C. By reference to Fig. 6, it will be seen that these jacks have teeth 49, whereby they are operated. These teeth are of sufficient 100 breadth to enable them to be engaged either by the dog on tappet 32AC, or by the dogs on tappets 32B¹C and 32B²C. This set of jacks 34AB¹B² may therefore be operated by any 105 one of these three dogs.

The jacks 34A (belonging to totalizer A) conform to the jacks 34AB¹B², except that the teeth thereof are too narrow to be engageable by any of the dogs on the tappets 32, except the dog which is on tappet 32A, 110 and to this extent said jacks 34A are distinguishable from the jacks 34AB¹B², which are capable of being actuated by two different kinds of tappets 32.

The jacks 34B¹, 34B² are the longest of 115 all, and have narrow teeth 51 so placed as to engage solely with the dogs on the tappet 32B.

Therefore the proper jacks only will be actuated at the proper time, to be determined by the travel of the carriage, and each dog will avoid all jacks except those which it is intended to actuate; so that, in effect, there are provided four computing heads or totalizers in a space usually occupied by three, with one of the totalizers acting as a gross totalizer for all the remaining three totalizers.

In operating the device, the tappets 32A, 32AC, 32B, 32B¹C, 32B²C are first adjusted 130

to their proper positions along the rod 31, so as to come into play when required during the travel of the carriage 7, to control the lifting of the index-pin bars 20 in the various groups. The carriage 7 may now be moved in letter-feeding direction to a point where tappet 32A engages the jack 34A of highest denomination (Figs. 3 and 8), that is, the first jack at the right of the group. At the same time tappet 32AC engages jack 34AC of highest denomination.

Upon now striking the numeral keys 1, the carriage 7 will move step by step in letter-feeding direction, so that tappet 32A will rock jacks 34A successively, and the tappet 32AC will rock the jacks 34AC accordingly. This causes the raising *seriatim* of the index-pin bars 20 for both the computing heads A and C simultaneously, so that the index-pins in two of the groups will be set by the key-actuated linkages 18.

The general operator can then be actuated by means of the handle 30, so that the numbers already written on the work-sheet will be run up in the computing heads A and C simultaneously, the head A acting as a column totalizer, and the head C acting as a gross totalizer. (During the writing of the remainder of the line, tappet 32A will be out of use and nothing will happen to totalizer A.)

The carriage 7 will be advanced, as by means of a tabulating mechanism, not shown, until the next computing zone or column is reached. The tappet 32B now comes into engagement with the highest denomination jack of the series 34B¹ (Figs. 4 and 9). At the same time, tappet 32B¹C engages the highest of the set of jacks 34AB¹B² which connect to the first minor totalizer B¹. With the writing of the digits of the number to be accumulated, which number will be limited to 99.99, the carriage 7 will travel step by step concomitantly actuating the jacks 34B¹ and 34AB¹B², so that the number may be set up or indexed on the pin-bearing rack bars 20 of the cross totalizer C and the first minor totalizer B¹. When these small numbers have been indexed by a setting of the pins 19, the general operator can then be actuated by a rocking of the handle 30 to run these numbers up in the computing heads B¹ and C. The cross totalizer C thus adds to the number which was already accumulated when acting in synchronism with the totalizer A, the small number which it now accumulates when acting in synchronism with the first minor totalizer B¹.

When this has been accomplished, the carriage 7 can be again advanced to reach the next computing zone or column in which the second minor totalizer B² will come into play. Under these conditions, the parts will be arranged as shown in Figs. 6 and 10,

with the tappet 32B coöperating with the jacks 34B² and the tappet 32B²C coöperating with the jacks 34AB¹B². The jacks 34AB¹B² can then be concomitantly actuated with the actuation of the jacks 34B², so that the numbers will be set up on the pin-bearing denominational bars for both the totalizers B² and C. After setting up, the handle 30 can again be actuated to run up these numbers in the second minor totalizer B² and the cross or gross totalizer C. The carriage may then be returned and the same operation repeated for the next line.

Taking up a specific example, suppose the following numbers are to be summed up vertically in their columns and also the gross total of the several columns obtained:

567,843.21	67.65	35.34	
534,621.81	65.76	25.42	85

Then the carriage 7 is started at its extreme right position and brought to the first computing zone or column by the tabulating mechanism, or otherwise, so that the tappet 32A will come into register with the jack 34A of highest denomination in the set corresponding to the totalizer A. At the same time the tappet 32AC will come into register with the jack 34AC of highest denomination in the set corresponding to the totalizer C. See Figs. 3 and 8. The denominational bar 20 of highest denomination for both the totalizers A and C will then be raised so that as the numeral key "5" is struck to print and set up the digit "5" (being the digit of highest denomination in the first number to be computed), then the "5" pin will be set up on two denominational bars 20, one for the totalizer A and the other for the totalizer C. The carriage 7 will then move a letter space, so that the next two denominational bars, one for the totalizer A and the other for the totalizer C, will be raised so that the "6" pin thereon can be set by a striking of the numeral key "6." This is continued for the rest of the digits (7,843.21) of the first number, the spaces for the comma and decimal point between the "7" and "8" and the "3" and "2" being taken care of by space jacks in the usual way. After the complete number has thus been set up, the general operator may be actuated by a rocking of the handle 30, so that this complete number will be simultaneously carried into both the totalizers A and C.

The carriage 7 may then be spaced to bring the next computing zone or column corresponding to the minor totalizer B¹ into action. At this point, the tappet 32B will come into register with the jack 34B¹ of highest denomination, at the same time that the tappet 32B¹C comes into register with the jack of highest denomination of the second section 34AB¹B² of the jacks 34AC 120

corresponding to the fourth digit column from the lowest in the totalizer C. (See Figs. 4 and 9.) The mechanism is then in a condition to set up the number "67.65," so that it may be later accumulated in both the totalizer B¹ and the gross totalizer C, the tappet 32B¹C having escaped the jacks of highest denomination of the group 34AC, so that the digits will be properly set up in 10 the gross totalizer C.

At this point there will be a denominational pin-bearing bar 20 connected to the fourth from the lowest computing wheel raised, not only in the minor totalizer B¹ but 15 also in the gross totalizer C, so that at the striking of the numeral key "6," the "6" pin will be set up for both the totalizers B¹ and C. The carriage is then moved a letter space to set up the number "7" for 20 both the totalizers B¹ and C, and so on until the whole number "67.65" is set up, when the general operator can be actuated to carry this number not only into the totalizer B¹ but also into the totalizer C. The totalizer B¹ not having accumulated any number previously, will merely show the number "67.65," while the totalizer C, having already accumulated the number "567,843.21," will show the addition of the number "67.65" 30 thereto, which will be "567,910.86."

The carriage 7 is then spaced again to bring into play the second minor totalizer B² to accumulate the number "35.34." When this occurs, the tappet 32B will have advanced to a point such that it will come into engagement with the jack of highest denomination of the set 34B². At the same time the tappet 32B²C will have reached the jack of highest denomination of the second section 40 34AB¹B² of the series of jacks 34AC corresponding to the totalizer C (see Figs. 5 and 10). The number "35.34" will then be set up, not only for the totalizer B², but also for the totalizer C, and that, too, with the digits 45 in the proper denominational columns. This number can then be carried simultaneously into the totalizers B² and C, so that the totalizer B² will exhibit the number "35.34," while the totalizer C will add this number 50 to the sum of the first two numbers already accumulated, giving the sum of "567,946.20," which will be exhibited in this gross totalizer. The carriage may be then returned and the platen 6 line-spaced to start the 55 writing and computing of the second line of numbers.

As in the case of the first line, the tappets 32A and 32AC will come into play simultaneously to control all of the jacks 34A and 60 34AC of the totalizers A and C, respectively. The first number in the second line, "534,621.81," will then be set up simultaneously for both the totalizers A and C, and can be run up into these totalizers by an actuation of the general operator, so that in 65

the case of the totalizer A, this number will be added to the number "567,843.21," giving the sum, "1,102,465.02," while the said number will be added to the gross total, "567,946.20," already accumulated in the 70 totalizer C, so that this gross totalizer will now exhibit the number "1,102,568.01."

The carriage 7 is then spaced to come to the second computing zone or column where the number "65.76" can be set up simultaneously for the totalizers B¹ and C, and can be carried into these totalizers so that the totalizer B¹ will exhibit the number "133.41," representing the sum of the numbers "67.65" and "65.76," while the totalizer C will exhibit the gross total so far obtained by the adding of the number "65.76" to that already accumulated, or, in other words, will exhibit the number "1,102,633.77."

The carriage is again spaced to bring into 85 play the minor totalizer B² so as to add the number "25.42" to the number "35.34" already accumulated therein. The number "25.42" will also be set up and carried into the gross totalizer C simultaneously with its 90 accumulation in the minor totalizer B². The minor totalizer B² will then exhibit the number "60.76," while the gross totalizer C will exhibit the number "1,102,659.19."

We will have then at the finish the individual sums of the vertical columns exhibited in the totalizers A, B¹ and B², the first being for a large number and the last two for smaller numbers. We will also have the gross total of all of the numbers, both large 100 and small, exhibited in the totalizer C. This action can be continued for any number of figures and by increasing or decreasing the number of totalizers the number of columns can also be varied.

If it is desired to have a more flexible arrangement, the modified form shown in Fig. 11 may be used. In this adaptation of the invention, the jacks 34B¹ and 34B², corresponding to the minor totalizers B¹ and B², 110 respectively, are made of different lengths, so that they can be operated by two different tappets 32B¹ and 32B², and not by the same tappet as in the case of the form shown in Figs. 1 to 10, inclusive. In the form shown 115 in Figs. 1 to 10, inclusive, the two minor totalizers were necessarily brought into play in succession, as the tappet 32B first actuated the set of jacks 34B¹ and then actuated the second set of jacks 34B². In this modified form, however, the tappets 32B¹ and 32B² can be placed at any desired points along the rod 31, so that the minor totalizers B¹ and B² to which they correspond, can be brought into play at any desired points in 125 the travel of the carriage; it not being necessary that they shall come into play in direct succession. It will thus be seen that in this form, the computing columns of small numbers can be widely separated if desired. 130

The tappets 32B¹ and 32B² of course are arranged to avoid the jacks 34A and 34AC of the other totalizers.

It has thus been shown how we may add three different columns, one with large numbers and two with small numbers, and accumulate both the large and the small numbers in the gross totalizer C, so that at the end of the operation we will have three column totals and a gross total; this also with a mechanism occupying a space normally occupied by but three totalizers. Of course it is to be understood that the number of totalizers is not limited to the number shown in this embodiment; more major totalizers or more minor totalizers might be used. On the other hand, the major totalizer A or one of the minor totalizers B¹ or B² might be omitted. The invention is also applicable even if the gross totalizer C were omitted.

Variations may be resorted to within the scope of the invention, and portions of the improvements may be used without others.

Having thus described my invention, I claim:

1. In a computing machine, the combination of a computing unit which may be used as two juxta-positioned independently operable minor units each to compute two columns of small numbers, a cross computing unit arranged to compute the aggregate of the numbers computed individually by said minor units, denominational selecting mechanism for all of said units, the denominational selecting mechanism for the parts of said juxta-positioned units being differently arranged for the two units so that said cross unit may be operative concurrently with either minor unit.

2. The combination of a major totalizer arranged to accumulate either large or small numbers; a minor totalizer arranged to accumulate solely small numbers; a denomination selector individual to each of said totalizers; a gross totalizer arranged to accumulate the aggregate of all the numbers accumulated individually in said major and minor totalizers, said gross totalizer being concomitantly operative selectively either with said major totalizer or with said minor totalizer, so as to simultaneously accumulate therein the same number that is being accumulated in the selected major or minor totalizer; and a multiple-denominational selecting system for said gross totalizer comprising a selecting member operative solely when said gross totalizer is operating at the same time as the major totalizer, and a separate selecting member operative solely when the gross totalizer is operating at the same time as the minor totalizer.

3. The combination of a major totalizer arranged to accumulate either large or small numbers; a plurality of minor totalizers arranged to accumulate solely small numbers;

a denomination selector individual to said major totalizer and to each of said minor totalizers; a gross totalizer arranged to accumulate the aggregate of all the numbers accumulated individually in said major and minor totalizers, said gross totalizer being concomitantly operative selectively either with said major totalizer or with any one of said minor totalizers, so as to simultaneously accumulate therein the same number that is being accumulated in the selected major or minor totalizer; and a multiple-denominational selecting system for said gross totalizer comprising a selecting member operative solely when said gross totalizer is operating at the same time as the major totalizer, and a plurality of separate selecting members, one corresponding to each minor totalizer, each operative solely when the gross totalizer is operating at the same time as the associated minor totalizer.

4. The combination with a computing mechanism, of jacks for controlling said computing mechanism, some of said jacks being broad jacks and others narrow jacks, and broad and narrow tappets for actuating said jacks.

5. The combination with a computing head, of denominational members for running up numbers in said computing head, numeral keys for determining the extent of movement of said denominational members, jacks for bringing said denominational members successively into play, a traveling carriage, and tappets carried by said carriage for actuating said jacks, certain of said jacks being of greater length than others of said jacks and certain of said tappets being of different effective reach than certain others of said tappets, so that certain of said tappets will actuate a portion of said jacks while certain others of said tappets will actuate all of said jacks.

6. The combination with a computing head, of denominational members for running up numbers in said computing head, numeral keys for determining the extent of movement of said denominational members, a series of jacks for bringing said denominational members individually into play, a traveling carriage, and a series of tappets carried by said carriage and arranged to actuate said jacks, said tappets being of different effective reach and said jacks being of different effective reach so that certain of said tappets will actuate certain of said jacks not actuated by certain others of said tappets.

7. The combination with a plurality of computing heads, of a plurality of sets of denominational members, one set individual to each of said heads, a series of numeral keys for determining the extent of movement of said denominational members, a set of jacks for each of said sets of denominational members, and a plurality of tappets, each tappet being of different effective reach and being arranged to actuate a different set of jacks, so that certain of said tappets will actuate certain of said sets of jacks not actuated by certain others of said tappets.

national members arranged to bring the same into play individually, a traveling carriage, and a series of tappets carried by said carriage, certain of said jacks being of greater effective reach than certain others of said jacks and certain of said tappets being of greater effective reach than certain others of said tappets so that the tappets will actuate solely jacks of accordant 10 putting heads.

8. The combination with computing wheels, of denominational members for running up numbers in said computing wheels, numeral keys for limiting the extent of movement of said denominational members, a series of jacks for bringing said denominational members into play individually, a traveling carriage, and a plurality of tappets carried by said carriage for actuating 20 said jacks, some of said jacks having a broad extension to be actuated by a plurality of said tappets of different effective reaches and some of said jacks having a narrow extension to be actuated by less of 25 said tappets than others of said jacks.

9. The combination with a typewriting mechanism, of a computing mechanism including a plurality of totalizers, and controlling means for according the denominations of the digits as computed by said totalizers with the denominations of the digits as typewritten, some of said totalizers acting in unison to compute the same numbers simultaneously, the range of travel of parts 35 of said controlling means for some of said totalizers overlapping the zone of the parts of the controlling means of others of said totalizers, said controlling means being graded for the different totalizers so as to 40 avoid the operation of the wrong totalizers.

10. The combination with a plurality of totalizers, of connections individual to each totalizer arranged to control the operation and activity thereof, and a series of tappets 45 for actuating said connections, said tappets being adjustable to selectively operate any two totalizers in unison, and graded so as to operate solely their accordant totalizers and avoid the operation of all other totalizers than those determined at any particular instant.

11. The combination with a totalizer including a series of number wheels, of a drive for said totalizer including individual driving members for the number wheels, and denominational selecting mechanism for said drive and said totalizer partitionable into sections so as to make of said totalizer a divided totalizer including two 60 totalizers each of smaller denominational capacity than the original totalizer.

12. The combination with a totalizer including a plurality of number wheels, of a series of denominational selecting elements 65 associated with said number wheels, some

of the said elements associated with the number wheels of said totalizer having a different range from others of said elements, and a plurality of coöperating members for bringing into play said selecting 70 elements, one of said members having a range to engage some of said selecting elements and escape others, while another of said members has a range to engage all of said selecting elements.

13. The combination with a major totalizer, of a minor totalizer of less capacity than said major totalizer, a gross totalizer coöperating at times with said major totalizer to compute the same numbers and at 80 times with said minor totalizer to compute the same numbers as computed thereby, said totalizers having a series of number wheels, individual actuating mechanisms for each totalizer, including individual actuating 85 members for each number wheel of the totalizer, and alternative selecting mechanism for determining whether all of said actuating members for said gross totalizer may be in action when said actuating members for said major totalizer are in action, or whether only a portion of said actuating members for said gross totalizer shall be in action with the corresponding actuating 90 members of said minor totalizer.

14. The combination with a totalizer having a plurality of number wheels, of actuating mechanism for said totalizer, selecting groups of elements for said actuating mechanism and said number wheels, and a 100 plurality of selectors coöperating with said groups, each selector coöperating solely with one group and a different group from the rest.

15. The combination with a major totalizer, of a minor totalizer, a gross totalizer, said totalizers including a plurality of number wheels, a group of denominational selecting elements for each of said totalizers, the order of successive action of the elements of each group being transposed with respect to the order of successive action of the number wheels of the corresponding totalizer, the one taking place in one direction and the other in just the opposite 115 direction, and selectors for said denominational selecting groups arranged to come into action so as to accord the action of all denominational selecting elements of the major totalizer and the gross totalizer, and also accord the denominational selecting elements of the minor totalizer with the corresponding elements of the gross totalizer while escaping the denominational selecting elements in the gross totalizer lacking in the denominational selecting group of the minor totalizer.

16. The combination with a plurality of primary totalizers of different denominational capacities, and a multiple drive for each pri- 130

mary totalizer, of a gross totalizer, a multiple drive for said gross totalizer, and controlling mechanism for according the drives of the several totalizers so that sections of the multiple drive for said gross totalizer will come into play corresponding in magnitude to the denominational capacity of the primary totalizer with which it is cooperating at any particular instant.

10 17. The combination with a plurality of totalizers, one of which is a gross totalizer, of selecting mechanism determining the activity of the totalizers, including a selector acting while in the zone of selection of the gross totalizer, but failing to select for certain denominations outside of the denominational capacity of the totalizer with which the gross totalizer is coöperating.

15 18. The combination of a computing unit including denominational selecting mechanism, said denominational selecting mechanism being divisible into separate units or entities and means for timing the action or bringing into play of the divided sections thereof.

20 19. The combination, with one or more item computing units including denominational-selecting mechanism, certain of said units being split into separate sections or entities by dividing the associated denominational-selecting mechanism and timing the action or bringing into play of the divided sections thereof; of a gross computing unit; and denominational-selecting mechanism for 25 the gross computing unit acting accordantly with the divided sections of the first-named selecting mechanism, so as to synchronize computation in the same digit columns of said gross computing unit and the active section of the split item computing unit.

25 20. The combination, with a pair of primary computing units of equal denominational range including a denominational-selecting mechanism for each, one of said primary units being split into separate sections or entities by dividing the associated denominational-selecting mechanism and timing the action or bringing into play of the divided sections thereof; of a cross computing unit having at least as great a denominational range as said primary units and including denominational-selecting mechanism for said cross computing unit acting accordantly with the divided sections of the selecting mechanism associated with the split primary computing unit, to synchronize computation in corresponding digit columns of said cross computing unit and the active section of said split primary computing unit, and also acting accordantly with the selecting mechanism associated with the other computing unit to synchronize computation in corresponding digit columns of said cross computing unit and said other primary computing unit.

21. The combination, with a major computing unit including a denomination-selector; of a computing unit having approximately the same number of computing wheels as said major unit, but split into two independently-operable minor units and having a denomination-selector individual to each of said minor units, the denomination selectors for said minor units being settable close together so as to conjointly occupy a lineal area which is less than that occupied by either the major or the split computing unit; and a gross computing unit concomitantly operating selectively either with said major unit, or with either minor unit, to simultaneously accumulate therein the same number that is being accumulated in the selected major or minor unit.

25 22. In a computing machine, the combination with a gross totalizer having a series of denominational members, selecting means for determining the activity of some of said denominational members only, and other and differently arranged selecting means for determining the activity of all of said denominational members.

30 23. In a computing machine, the combination with a totalizer, of denominational members therefor divided into two groups, whereby said totalizer may be used as two minor totalizers, a gross totalizer, denominational members therefor, a selector for successively operating said groups of denominational members, a selector for operating the denominational members of said gross totalizer corresponding in denomination to the denominational members of the first group of members concomitantly with the operation of said first group, and a selector for operating the same group of denominational members of said gross totalizer concomitantly with the operation of the denominational members of said second group.

35 24. In a computing machine, the combination with a major totalizer, a totalizer which may be operated as independently operable minor totalizers, a gross totalizer, all of said totalizers having adjacent denominational members, selecting means for determining the activity of a part of said denominational members of said gross totalizer concomitantly with corresponding denominational members of one of said minor totalizers, and a differently arranged means for determining the activity of all of said denominational members of said gross totalizer concomitantly with all the denominational members of the major totalizer.

40 25. In a computing machine, the combination with a major totalizer, a totalizer which may be operated as independently operable minor totalizers, and a gross totalizer, all of said totalizers having denominational members, two separate selectors each

determining the activity of a part of said gross totalizer, and another selector for determining the activity of all of said denominational members of said gross totalizer,
5 means for determining the activity of one of said minor totalizers concomitantly with the action of one of the two first recited selectors, means for determining the activity of another of said minor totalizers concomitantly with the action of the other of said two first-mentioned selectors, and means for determining the activity of said major totalizer concomitantly with the action of the last-mentioned selector for said gross totalizer.
10
15

26. In a computing machine, the combi-

nation with a totalizer, of denominational members therefor, said totalizer capable of being divided into independently operable minor totalizers, a selector for successively 20 operating said denominational members, a gross totalizer, denominational members therefor, and a plurality of separate 25 selectors for operating the denominational members associated with said gross totalizer concomitantly with the operation of the denominational members associated with the said minor totalizers.
